WILLIAM N. BARTHOLOMEW, OF NEWTON, MASSACHUSETTS.

Letters Patent No. 86,272, dated January 26, 1869.

IMPROVEMENT IN SLATE-FRAMES.

The Schedule referred to in these Letters Patent and making part of the same.

To whom it may concern :

Be it known that I, WILLIAM N. BARTHOLOMEW, of Newton, in the county of Middlesex, and State of Massachusetts, have invented certain new and useful Improvements in Slates; and I hereby declare the following to be a full, clear, and exact description of the same, reference being had to the accompanying drawings, in which—

Figure 1 is a perspective view of a slate, made in accordance with my invention, showing the position which the examples to be copied occupy when they are in use.

Figure 2 is a side view of the same, exhibiting more clearly the position of the copy-cards with relation to the eye of the pupil or copyist.

My invention relates to the attachment to a slate of cards containing the examples or figures to be reproduced upon the slate by the copyist; and

Its object is to combine the cards with the slate, in such manner that, first, no part of the slate-surface will be occupied by the copy-card; second, the card-surface will be placed perpendicularly, or nearly so, to the plane of vision of the copyist.

It is manifestly advantageous to leave the slate-surface free and uncovered, so that the whole may, as far as possible, be utilized; and, again, by placing the card so that its plane shall be about perpendicular to the plane of vision, the copyist is enabled to see the true form of the outline of the figure to be copied. When the copy lies flat on the slate or desk, it is viewed obliquely, and hence is seen in perspective. Vertical lines in the copy will appear distorted by foreshortening.

The manner in which my invention is or may be carried into effect will be readily understood by reference to the accompanying drawings, in which—

A represents the slate proper;
B, the slate-frame; and

C, the case containing the copy-cards.

In order to have the slate-surface entirely unoccupied, and to hold the copy-cards at the required angle with respect to the slate, I form in the frame a slot, *a*, whose sides are cut, so as to stand at the angle desired. In this slot, the case *C* is inserted, and stands, its degree of obliquity being governed by the inclination of the sides of the slot. In practice, it will be found best to make the angle of inclination from one hundred and twenty to one hundred and thirty degrees, but of course it may be varied, according to circumstances.

In case but one copy-card is to be held in the slate at a time, a narrow slot, such as represented at *b*, may be made, in which the lower edge of the card is inserted.

Again, if the frame or case *C*, which supports the cards, be made of wood or other stiff material, the slot *a* may have perpendicular sides, and the case may be provided with a bottom ledge or flange, with perpendicular sides also, which will fit in the slot, the case in this instance being set at the required angle to its flange or base, in order to give it the necessary obliquity.

Having now described my invention, and the manner in which the same is or may be carried into effect,

What I claim, and desire to secure by Letters Patent, is—

The formation, in the slate-frame, of slots to receive and hold in position the copy-card or cards, or the frame which supports the same, substantially as and for the purposes herein shown and set forth.

In testimony whereof, I have signed my name to this specification, before two subscribing witnesses.

WM. N. BARTHOLOMEW.
